DESIGN.

—o—
P. GROEBER.

WALL PAPER.

No. 15,238.

Patented Aug. 12, 1884.

UNITED STATES PATENT OFFICE.

PAUL GROEBER, OF NEW YORK, N. Y.

DESIGN FOR WALL-PAPER.

SPECIFICATION forming part of Design No. 15,238, dated August 12, 1884.

Application filed April 11, 1884. Term of patent 34 years.

To all whom it may concern:

Be it known that I, PAUL GROEBER, a citizen of the United States, residing in the city of New York, county and State of New York, 5 have invented and produced a new and original Design for Wall or Ceiling Covering, which is especially intended as a frieze.

The drawing represents a front plan view of the design.
10 The design is floral in its character, and treated in the Renaissance style.

The center of the design shows a group of four expanded flowers, *aaa*, having five petals each, and a rosette in the center of each flower. 15 Trailing branches *bb* extend from left to right, on either side of which peonies and other flowers, *cc*, in bloom, are arranged in irregular order, in one instance overlapping the lower border of the design. The foliage, in graceful

profusion, is seen in every part of the central 20 part of the pattern, and overlaps both the upper and lower border of the design.

The interstices of the design are filled in with a ground of line-work forming irregular crystals. The whole is bounded by a band, top and 25 bottom, consisting of fillets and perpendicular bars arranged at regular distances, which bars are shaded with horizontal lines. The space between the bars is filled with three perpendicular lines.

I claim—

The design for a wall or ceiling covering, shown in the print accompanying this description.

PAUL GROEBER.
